UNITED STATES PATENT OFFICE.

ERNEST W. BAXTER, OF VAN WERT, OHIO.

GOVERNOR FOR GAS-ENGINES.

1,376,503.

Specification of Letters Patent.

Patented May 3, 1921.

Application filed December 17, 1919. Serial No. 345,578.

To all whom it may concern:

Be it known that I, ERNEST W. BAXTER, a citizen of the United States of America, and resident of Van Wert, in the county of Van Wert and State of Ohio, have invented certain new and useful Improvements in Governors for Gas-Engines, of which the following is a specification.

This invention relates to improvements in governors for gas engines and the object thereof is to provide means for regulating the admission of fuel to the engine either through the throttle or by interrupting the action of its exhaust valve, or both, so that the action of the engine may be maintained closely at a predetermined velocity though subjected to loads varying widely in character.

The object of the improvement is accomplished by the construction illustrated in the accompanying drawings in which:

Figure 1 is a side elevation of a gas engine with a portion thereof broken away and showing the invention in connection therewith; and

Fig. 2 is a plan view of the same showing a part thereof broken away and in section.

Similar characters of reference indicate corresponding parts in both views and having reference now to the same:

1 is the bed of the engine upon which is supported the crank shaft 2, 3 is the engine cylinder, and 4 and 5 are fly wheels respectively mounted upon the corresponding opposite ends of the crank shaft. 6 is a back gear actuated by a pinion 7 on the crank shaft, the back gear being provided with a cam 8 adapted to actuate the push bar 9. A lever 10 is pivotally mounted at the rear end of the cylinder 3 and is adapted to be actuated by the push bar 9 so as to open the exhaust valve 11 periodically as the engine rotates in the customary manner. A governing means comprising a pair of weighted levers 12 are pivotally supported in connection with the fly wheel 5 and each has engagement with a grooved sleeve 13 that is loosely mounted on the crank shaft adjacent the fly wheel so that as the weighted levers spread apart the sleeve is moved longitudinally.

A rocking member 14 is pivotally mounted upon a bracket 15 that projects from the side of the bed 1 and has engagement at its forward end with the grooved sleeve 13 so as to be oscillated thereby as the latter is moved longitudinally upon the crank shaft

by the weighted levers. The rear end of the rocking member 14 has pivoted thereon a detent member 14' which is adapted to be shifted into the path of a stop 16 that is fixed upon the push bar 9 so that the latter will be detained in its outer position when thus engaged and the exhaust valve consequently held open. The rocking member has an outwardly extending arm 17 through which loosely extends a throttle rod 18, there being a threaded adjusting sleeve 19 on the rod that bears against the adjacent face of the arm 17. The opposite end of the throttle rod has connection with a crank 20 which actuates the throttle valve 21. A bracket 22 extends from the side of the engine cylinder and has a threaded adjusting sleeve 23 extending therethrough, and upon the throttle rod 18 is a fixed flange 24, there being a compression spring 25 arranged interveningly between the flange 24 and the forward end of the adjusting sleeve 23, the action of the spring being such that the throttle valve tends to open for the admission of fuel into the engine cylinder.

As a means of throwing the detent member out of action it is formed with a transverse slot 26 in its forward end through which a binding screw 27 extends and which engages in the rocking member so that the detent member may be adjustably turned upon its pivot 28 and secured in relation therewith. Thus when so desired, the detent member may be positioned out of the path of the stop 16 so that as the engine operates, the exhaust valve will not be interrupted. Also the crank 20 of the throttle-valve has a set-screw 29 which may be loosened so that the crank actuates without affecting the throttle valve, and a slotted segment 30 has fixed connection with the throttle valve and is adapted to be held in adjusted positions by a clamp screw 31 so that the throttle valve may be set at any desired degree of opening.

In the operation of the invention the engine is governed by the dual mechanism, one phase of which is based upon the "hit and miss" principle and the other operating upon the "throttle" principle, both of which have been separately established in the art.

In the present invention a mechanism is employed involving the employment of both of these principles in coöoperative relationship. In this manner the engine does not receive a full charge of fuel when idling which generally occurs in engines having

only the "hit and miss" governor and which causes a violent acceleration in the velocity of the engine. By the present construction the charges of fuel drawn into the engine 5 cylinder occur with varying frequency during the progress of the cycles of the engine according to the variations in its velocity, and the charges of fuel when admitted to the engine cylinder quantitatively vary as the 10 throttle turns with variations in the velocity of the engine. Thus, excessive charges of fuel are not drawn into the cylinder but the fuel is admitted in charges that vary in quantity proportionate to the varying load 15 of the engine and only when running at or below its normal velocity.

An especial feature of the invention is the provision for independently throwing out of action the detent member and the throttle, 20 so that by making simple adjustments the engine may be arranged to be governed by either the "hit and miss" or by the "throttle" principle without interfering with the other. This is desirable especially 25 when the engine is used for driving various loads which differ in extent of resistance and constancy.

What I claim is:—

1. In a governor for gas engines having a 30 throttle-valve and exhaust valve, the combination of a governing mechanism of the "hit and miss" type for the exhaust valve, and a governing mechanism of the throttle type for the throttle-valve, arranged in coöperative 35 relation with the former mechanism, each governing mechanism being adapted to be independently thrown out of action.

2. In a governor for gas engines having a throttle-valve and exhaust valve and mech- 40

anism for actuating the exhaust valve, a governing member, a rocking member actuated by the governing member; a detent member adjustably mounted in connection with the rocking member adapted to interrupt the actuating member; means in connection with 45 the rocking member for actuating the throttle valve, said detent member and throttle valve actuating means each being adapted to be independently thrown out of action; and means for adjustably setting 50 the throttle valve.

3. In a governor for gas engines having a throttle valve and exhaust valve, the combination of a governing means; a "hit and miss" mechanism actuated by the governing 55 means adapted to interrupt the exhaust valve; a "throttle mechanism" actuated by the governing means for automatically actuating the throttle; means in connection with the "hit and miss" mechanism for throwing the same out of action; means for independently throwing the throttle mechanism out of action; and means for securing the throttle valve adjustably in position.

4. In a governor for gas engines having a 60 throttle valve and exhaust valve, a governing means including mechanism for automatically regulating the action of each of said valves; and means for adjusting said mechanism for independently throwing it out of 65 regulating relation with either of said valves.

In testimony whereof I affix my signature, in presence of two witnesses.
